CLAIM

The ornamental design for a motorcycle brake cylinder, as shown and described.

DESCRIPTION

FIG. 1 is a perspective view illustrating the environment for a motorcycle brake cylinder according to our invention;

FIG. 2 is a top view thereof;

FIG. 3 is a left side view thereof;

FIG. 4 is a right side view thereof;

FIG. 5 is a bottom view thereof;

FIG. 6 is a front view thereof; and,

FIG. 7 is a rear view thereof.

Those portions of the drawings represented by broken lines are intended to illustrate the environment for the motorcycle brake cylinder according to our invention and form no part of our invention.

1 Claim, 2 Drawing Sheets
